UNITED STATES PATENT OFFICE

2,513,464

SEAM PRESSING MACHINE

Harry D. Elliott, Wenham, Mass., assignor to
 United Shoe Machinery Corporation, Flemington, N. J., a corporation of New Jersey

Application July 23, 1948, Serial No. 40,395

4 Claims. (Cl. 69—7)

1

This invention relates to machines for pressing seams formed in shoe parts, for example, the back seams of shoe uppers, and it is herein illustrated and described as embodied in a machine of the type disclosed in United States Letters Patent No. 2,440,675, granted May 4, 1948, upon the application of Alfred S. Clark and Edward M. Spence, Sr. Machines of this type are provided with a seam pressing roll of large diameter and with a pair of smaller work feeding rolls between which the pressing roll extends. A spring-pressed support is provided for yieldingly holding the work against the pressing roll and the feed rolls. The work is presented to the machine with the unfinished side, i. e., the flesh side of the leather, in contact with the feed rolls and the pressing roll.

The back seam to be pressed may, at the time the operation is performed, be the only connection between the two pieces of upper material which it joins. In such a case, where the work piece consists of a pair of quarters having no connection to each other except through the back seam, there is no difficulty in removing the work piece, hereinafter termed an open work piece, from the machine after the back seam has been pressed. However, it is often desirable to perform the seam pressing operation after the quarters have been stitched to a vamp to form a complete upper, or to perform it upon an upper which consists of a single piece of material having its rear portions joined by the back seam. In such cases the work piece forms a ring-like structure completely enclosing a central opening and having a back seam which extends from the periphery to the central opening. After this closed upper has been fed to cause the back seam to traverse the operating instrumentalities of the machine from the periphery to the central opening, some provision must be made for its removal from the machine, either by a further unnecessary feeding operation or by separating the work-engaging instrumentalities to permit withdrawal.

It is an object of the present invention to provide a seam pressing machine suitable for operation upon closed uppers as well as upon open work pieces, and which is constructed and arranged for convenience of adjustment and operation.

In accordance with a feature of the invention, the illustrated machine is provided with a stop for limiting the movement of the spring-pressed work support toward the pressing roll and with means for adjusting the position of this stop, and it is provided also with means for adjusting the pressure exerted by the spring, each of these adjusting means being capable of being operated without affecting the other.

In accordance with a further feature, the 60 all similar, in their construction and in their

2

work support is arranged for ready removal to an out-of-the-way position to enable a stack of closed uppers which have accumulated around it to be removed.

In accordance with a still further feature, the 5 pressing roll and the coaxial feed rolls, together with the instrumentalities which support and drive them, are carried by an overhanging bracket extending from a single standard which 10 is positioned at one side only of the operator to permit a maximum degree of freedom for manipulation of the work.

These and other features of the invention, including certain details of construction and combinations of parts, will be described in connection with an illustrative machine and pointed out in the appended claims.

Referring now to the accompanying drawings, Fig. 1 is a front elevation of an illustrative 20 machine embodying the invention;

Fig. 2 is an end elevation of the machine;

Fig. 3 is a sectional plan view taken on the line III—III of Fig. 4, showing portions of the 25 supporting and driving instrumentalities;

Fig. 4 is a sectional elevation taken on the line IV—IV of Fig. 3;

Fig. 5 is a detail view, with a cover plate removed, taken in the direction of the arrow V on Fig. 2;

Fig. 6 is a detail view similar to Fig. 5 showing the above-mentioned cover plate in position and with a Hurley back stay guide mounted thereon;

Fig. 7 is an end elevation of the base portion 30 of the frame;

Fig. 8 is a view taken in the direction of the arrow VIII on Fig. 2 showing certain mechanism within the base of the frame;

Fig. 9 is an end elevation of the lower portion 35 of the frame showing the work support moved to an out-of-the-way position; and

Fig. 10 is a detail view in end elevation illustrating the passage of a work piece through the machine.

The illustrated machine is adapted to operate upon a work piece W (a fragment of which 45 is shown in Figs. 6 and 10). This work piece W consists of a pair of quarters joined together by a line of stitching S to leave a seam ridge R. The work piece W, as shown herein, has been turned inside-out for presentation to the machine. The operation consists in the flattening and ironing of the ridge R.

The work-engaging instrumentalities of the 50 illustrated machine comprise a driven seam pressing or seam rubbing roll 10 of large diameter, a work support 12, a pair of driven feed rolls 14 and 16, a pair of seam ridge guides 18 and 20 (Fig. 5), a seam crease guide 22 and a guide 24 for Hurley back stays. These parts are 55 all similar, in their construction and in their

mode of operation upon a work piece, to corresponding parts of the machine disclosed in Letters Patent No. 2,440,675, above mentioned. However, as will appear from a reading of the following description, the instrumentalities for driving and supporting certain of these parts are new.

The main portion of the frame of the illustrated machine consists of a hollow casting having a base portion 26 adapted to be secured to a work bench, a column 28 extending up from the right-hand end of the base and a substantially horizontal arm 30 extending from the upper portion of the column and overhanging the base. The left-hand end of the base portion 26 is closed by a cover plate 31. The left-hand end of the arm 30 is closed by a wall 32 (Fig. 3) against which is secured an end housing 34. The right-hand end of the housing 34 is closed by a wall 33, a part of which bears against the outer face of the wall 32. An arcuate recess 35 is formed in the wall 33 to accommodate the seam pressing roll 10. The left-hand end of the end housing 34 is covered by a plate 36. A screw 38 (Figs. 2 and 4) extending through both the cover plate 36 and the end housing 34 and threaded into the wall 32 helps to secure the cover plate and the end housing to the arm 30. Another screw 40 extending only through the end housing 34 assists the screw 38 in holding the end housing to the arm 30. A third screw 42 (Fig. 4) threaded into the end housing 34 helps to secure the cover plate 36 to the end housing.

The seam pressing roll 10 is fixed upon a shaft 44 (Figs. 2 and 3) the left-hand end portion of which is journaled in a bearing 46 mounted in a boss 48 extending from the end wall 32. The right-hand end of the shaft 44 is journaled in a bearing 50 (Fig. 1) which is mounted in a cover plate 52 secured to the right-hand face of the column 28. These bearings hold the shaft 44 against endwise movement. Secured upon the shaft 44 adjacent to the right-hand end thereof is a gear 54 which is driven by a gear 56 mounted on a shaft 58. The left-hand end of the shaft 58 is of reduced diameter and is journaled in a bearing 60 secured in a bracket 62 carried by the cover plate 52; an intermediate portion of the shaft 58 is journaled in a bearing 64 carried by the cover plate 52. Mounted upon the right-hand end portion of the shaft 58 are a pair of fixed and loose pulleys 66 and 68 respectively. A belt 70 driven from any suitable source of power may be shifted from the loose pulley 68 to the fixed pulley 66 to drive the machine.

The feed roll 16 (Fig. 1) is adjustably secured upon the left-hand end of a shaft 72 by a set-screw 74. The shaft 72 is journaled in a bearing bushing 76 positioned a little to the right of the feed roll 16 and mounted in a boss on the end wall 32; and it is journaled also in a bearing bushing mounted in a boss 80 extending up from the lower wall of the arm 30. The shaft 72 is free to slide endwise in its bearings and it is urged toward the left, as seen in Fig. 1, by a coil compression spring 82, the right-hand end of which bears, through a washer, against one of a pair of thrust bearings 84 backed by the boss 80. The left-hand end of the spring 82 bears against a collar 86 adjustably secured by a set-screw 85 to the shaft. Secured upon the right-hand end of the shaft 72 is a gear 88 which meshes with an idler gear 90 mounted upon a stud (not shown) secured in the boss 80. A

finished surface on the adjacent face of the gear 88 engages the other thrust bearing 84 to limit the left-hand movement of the shaft 72 under the influence of the spring 82. The idler gear 88 is driven by a gear 90 secured upon a shaft 92, the right-hand end portion of which is journaled in a bearing 94 secured in the bracket 62. The shaft 92 extends to the left through openings in the walls 32 and 33, and its left-hand end portion is journaled in a bushing mounted in the cover plate 36. Secured upon the right-hand end of the shaft 92 is a bevel gear 98 which is driven by a bevel gear 100 secured upon a vertical shaft 102, the end portions of the shaft 102 being journaled in bearings 104 and 106 mounted in the bracket 62. Fixed upon the shaft 102 is a worm wheel 108 which is driven by a worm 110 on the shaft 58.

The feed roll 14 is driven in the following manner: Mounted on the shaft 92 (see Figs. 3 and 4) within the end housing 34 is a gear 112 which drives a train of idler gears 114, 116, 118 all mounted upon studs carried by the cover plate 36. The idler gear 118, which is the last of the train, drives a gear 120 secured upon the left-hand end portion of a shaft 122 which is slidably and rotatably mounted in a bearing bushing 124 carried by the end housing 34 and in a bearing bushing 125 carried by the cover plate 36. A setscrew 126 secures the feed roll 14 on the right-hand end portion of the shaft 122 with provision for endwise adjustment.

The feed roll 14 is urged to the right by a coil compression spring 128 (Fig. 1) housed in a bore in the wall of the end housing 34. The right-hand end of the spring 128 abuts against the left-hand end of a pressure adjusting screw 130 threaded into said bore. The left-hand end of the spring 128 bears against a plunger 132 housed in said bore and it transmits the thrust of the spring to an end knob of a thrust rod 134. The left-hand end of the rod 134, which is also rounded to form a knob, engages a socket formed in one end of a lever 136 fulcrumed on a pin 138 carried by a boss 140 extending from the cover plate 36. The opposite end of the lever 136 similarly engages a knob 142 formed on the left-hand end of the shaft 122. Movement of the feed roll 14 to the right under the influence of the spring 128 is limited by the engagement of a finished surface on the gear 120 with a washer which is backed by the bushing 124.

It is evident from the above description that the seam pressing roll 10 will be driven at relatively high speed and that the feed rolls 14 and 16 will be driven, both in the same direction, at lower speeds. The directions in which these rolls rotate are indicated by arrows on Fig. 2. The feed rolls 14 and 16 will be urged toward each other to their stopping positions by their springs 128 and 82 respectively and will yield away from each other to accommodate irregularities of thickness in the work pieces. Axial adjustment of the feed rolls 14 and 16 is made by loosening their set-screws 126 and 74 and sliding the feed rolls along their shafts.

For supporting the seam ridge guides and the Hurley back stay guides, there are provided a pair of L-shaped brackets 144 and 146, both of which are shown in Fig. 5 and one of which appears in Fig. 2. The bracket 144 is secured to a finished surface formed on the top of the end wall 32 by a pair of screws 148 threaded into the top of the end wall and extending through slots in the bracket to permit forward and rearward adjust-

ment of the latter. The L-shaped bracket 146 is similarly secured to a finished surface 150 (Fig. 4) formed on the top of the wall 33 of the end housing 34. A pair of screws 152 threaded into the end housing and extending through slots in the bracket 146 permit forward and rearward adjustment of the latter. The brackets 144 and 146 are similar to each other except for the fact that integral with the bracket 144 and extending substantially to the bracket 146 is a filler lug 154. When the machine is assembled the inner or right-hand face of the bracket 146 is substantially in engagement with the left-hand face of the lug 154.

The seam ridge guide 18 (Fig. 2) is secured by a screw 156, with provision for lateral adjustment, to a block 157 which is secured by a screw 159, with provision for heightwise adjustment, to the lower portion of a bar 158. The upper portion of the bar 158 is pivotally mounted upon a pin 160 secured in the bracket 146. The bar 158 hangs in a groove 162 formed in the outer face of the bracket 146, the groove being wide enough to afford some limited freedom of swinging movement to the bar. The seam ridge guide 20 is similarly secured upon a depending bar 164 which pivotally depends from a pin 166 secured in the bracket 144. It has some limited freedom of swinging movement in a groove 168 formed in the outer face of the bracket 144. From a reading of the foregoing description it will be evident that the seam ridge guides 18 and 20 are similar in construction and mounting to the corresponding members of the machine disclosed in United States Letters Patent No. 2,440,675, above mentioned. They are also urged toward each other by leaf springs not shown herein but fully disclosed in said patent.

The Hurley back stay guide 24 (Figs. 2 and 6) is pivotally mounted upon a shoulder screw 170 extending through a cover plate 172 which is clamped against the face of the bracket 144 by the screw 170 and two other screws threaded into holes 174 (Fig. 5) in the filler lug 154. This guide, which is shown in Fig. 6 in its neutral position, is operated through a linkage 176 by a treadle which is in all respects similar to corresponding mechanism disclosed in said Letters Patent No. 2,440,675. A slide 178 (Fig. 2), having a knob 180 for the convenience of the operator, can be moved down to serve as a stop for the purpose of maintaining the guide in its neutral position.

It is evident that, by reason of the construction so far described, the end housing 34 can readily be removed to afford access to the seam pressing roll 10 or for other reasons, and it can readily be replaced. Such removal and replacement of the end housing 34 do not disturb the seam ridge guide 20 or the Hurley back stay guide 24, since these members are carried by the horizontal arm 30 of the machine frame and not by the end housing. Although the feed roll 14 and the seam ridge guide 18 are carried by the end housing, their adjustment and the adjustment of the compression of the spring 123 are not affected by the removal and replacement of the end housing, since the parts involved in the adjustments are all carried bodily as a unit by the end housing.

The work support 12 consists of a central stationary disk positioned between two anti-friction side disks which rotate idly in the direction of the arrow on Fig. 2. All three disks are similar to corresponding members of the machine dis-

closed in Letters Patent No. 2,440,675 and they are mounted on a pin 182 (Fig. 2) secured between a pair of ears 184 (see also Fig. 1) which extend up from a plate 186 secured to a slide 188 in the form of a plunger 188. A guideway formed in a carrier or movable bracket 190 guides the plunger 188 for heightwise movement. Housed in a bore extending up into the lower end of the plunger 188 is a compression spring 192 the upper end of which bears against the upper end (i. e., the base) of said bore and the lower end of which bears against the upper end of an abutment screw 194 extending freely, i. e., non-threadedly, into the bore and having a knurled head. The screw 194 is threaded up through a cup-shaped cover 196 which is secured by screws 198 to a flange 200 extending radially from a tubular nut 202 having external threads and a smooth bore in which the lower portion of the plunger 188 is slidable. This nut 202 is threaded into a counterbore formed in the bracket 190 coaxial with the guideway for the plunger 188. A lock nut 204 threaded on the screw 194 engages a boss on the cover 196 to hold the screw 194 in adjusted position. The cover 196, by reason of its shape and the manner of its attachment to the nut 202, encloses a space 206 below the flange 200. Housed within this space and engaging an annular groove formed in the lower end portion of the slide 178 is a U-shaped washer 208. It is evident that the upward thrust of the spring 192 will urge the work support 12 up as far as permitted by the engagement of the U-shaped washer 208 with the lower end face of the nut 202 which thus serves as a stop, and that turning of the nut 202, which is facilitated by a knurled surface on the exterior of the cover 196, will adjust the stopping position of the work support heightwise without changing the compression of the spring 192. It is also evident that turning of the screw 194 (after the lock nut 204 has been loosened) serves to adjust the compression of the spring 192 without changing the upper stopping position of the work support 12.

The seam crease guide 22 has a depending shank 207 which is clamped by screws 209 to a block 211. The screws 209 are threaded into the plunger 188. The block 211 slides in a guide slot formed in the wall of the bracket 190 and, being clamped to the plunger by the screws 209, it holds the plunger against turning.

When working upon closed uppers the work support 12 may be moved from its operating position as shown in Fig. 2 to an out-of-the-way position as shown by full lines in Fig. 9 to facilitate the removal of a stack of closed uppers which have accumulated around the upstanding portion of the bracket 190. To provide for such movement of the work support, the bracket 190 is made in the form of a generally L-shaped member having a base which is clamped by screws 210 to a block 212. The block 212 and the base of the bracket 190 extend through a hole 213 (Fig. 1) in the top and front walls of the base portion 26 of the frame. Secured between the cover plate 31 and a boss within the base portion 26 is a stationary bearing pin 214 upon which the block 212 is fulcrumed for tilting movement. The block 212 is notched to provide between it and the base portion of the bracket 190 a guideway 216 in which is slidably mounted a lower bearing block 218 engaging the bottom of the guideway and an upper bearing block 220 engaging the top of the guideway. The bearing blocks 218 and 220 are not in contact with each

other but they are cylindrically grooved to engage an eccentric portion 222 of a crank comprising a shaft 224 (see also Fig. 8) journaled for pivotal movement in a bearing formed in a boss 225 depending from the top of the base portion 26 of the frame and in another bearing formed in the cover plate 31, the axis of the crank shaft 224 being parallel to that of the bearing pin 214. Integrally connecting the eccentric portion 222 with the bearing portions of the shaft 224 are a pair of crank arms 226. The bearing blocks 218 and 220 are held against axial movement along the eccentric portion 222 by their engagement with finished surfaces formed upon the crank arms. Secured upon one end 15 of the crank shaft 224 by a pin 228 is a hand wheel 230. Extending radially from the hub of the hand wheel 230 is a pin 232 which is engageable, when the wheel is turned in one direction, with a stop pin 234 secured in the cover plate 31. When the hand wheel is turned in the opposite direction the pin 232 is brought into engagement with another stop pin 236 also secured in the cover plate 31. Turning of the hand wheel 230 in the direction of the arrow, as shown in Fig. 7, will bring the work support 12 from its operating position as shown in Figs. 2 and 7 to its out-of-the-way position as shown in full lines in Fig. 9. As the hand wheel 230 is thus turned, the eccentric portion 222 of the crank travels up from the position shown in Fig. 2 to the position shown in Fig. 9, causing the bracket 190 to swing in a clockwise direction about the fulcrum pin 214. The limit of such outward movement of the bracket 190 is determined by the engagement of the pin 232 with the stop 236. When the work support is in this position the stack of closed uppers may readily be removed. The work support is returned to its operating position by turning the hand wheel 230 in a clockwise direction, as seen in Fig. 7, until the pin 232 engages the stop 234 which is so positioned as to enable the eccentric portion 222 of the crank shaft just barely to pass its dead-center position with respect to the operative faces of the guideway 216. Because of this arrangement, any force tending to swing the bracket 190 inwardly in a counter-clockwise direction will be resisted by a tension in the crank arms 226, while any accidental force tending to swing the bracket 190 outward in a clockwise direction will be resisted by the stop 234.

Having thus described my invention, what I claim as new and desire to secure by Letters Patent of the United States is:

1. In a machine of the class described, a work support, a slide upon which the work support is mounted, a bracket having a guideway for said slide, a spring having one of its ends bearing against the slide to urge the slide along the guideway, an abutment for the other end of the spring, a stop for limiting the movement of the slide in its guideway under the urge of said spring, said stop being secured to said bracket with provision for adjustment of the stop in the direction of movement of the slide, and means for securing said abutment to said stop with provision for adjustment of the abutment in the direction of movement of the slide.

2. In a machine of the class described, a work support, a plunger upon the upper end of which the work support is mounted, a bracket having

5 a guideway for said plunger, a tubular nut surrounding the plunger adjacent to the lower end thereof and threaded into said bracket, the plunger being slideable in the nut, the nut having an outwardly extending flange below the bracket and the plunger having an annular groove adjacent to its lower end, a U-shaped washer engaging said groove and engageable with the lower end of the nut to stop the upward movement of the plunger, a cup-shaped cap secured to said flange and housing said washer, the plunger having an axial bore extending up from its lower end, an abutment screw threaded up through said cap and extending freely into said bore, and a compression spring housed within said bore, the upper end of the spring bearing against the upper end of the plunger to urge the plunger up toward stopping position and the lower end of the spring bearing against the upper end of the abutment screw.

3. In a machine of the class described, a work support, a carrier for said work support, a bearing upon which said carrier is pivotally mounted for swinging movement of the work support toward and from an operating position, an operator-controlled crank, a pivotal bearing for said crank having an axis parallel to the axis of the first-mentioned bearing, a sliding connection between the crank and the carrier for swinging the carrier about the first-mentioned bearing when the crank is turned, and a stop for limiting the movement of the crank when the crank is turned to bring the work support from an out-of-the-way position into operating position, said stop being positioned to stop the crank immediately after the crank has passed its dead center position in the course of such turning, whereby accidental forces tending to move the work support toward its out-of-the-way position will be resisted by the stop, and accidental forces tending to move the work support in the opposite direction will be resisted by the crank in its dead center position.

4. In a seam pressing machine, a rotary seam pressing tool, a driven shaft, a bearing for said shaft, a frame having a horizontal overhanging arm in which said bearing is mounted, said shaft having an unsupported end portion extending beyond said bearing, said tool being mounted upon the unsupported end portion of said shaft, a pair of coaxial feed wheels disposed on opposite sides of said tool, a pair of coaxial shafts parallel to said tool shaft and having a space between their adjacent ends, the feed wheels being mounted on the adjacent end portions of said shafts, a bearing for one of said shafts mounted in said arm, a housing supported only by said arm and extending horizontally from said arm beyond said tool, a bearing for the other feed wheel shaft mounted in said housing, and driving means for said feed wheels.

HARRY D. ELLIOTT.
